BEDSIDE ADJUSTABLE TABLE

Melton H. Wright, Tupelo, Miss., assignor of one-third to Cena Jennings, Tupelo, Miss.

Application May 4, 1935, Serial No. 19,851

1 Claim. (Cl. 311—29)

My invention relates to improvements in tables and particularly to an adjustable table for attaching to beds.

It is an object of the invention to provide a bed table which may be easily and firmly attached to the frame of a bed consisting of a plurality of swiveled sections which permit the table to be swung over and away from the bed and which may also be vertically adjusted to raise or lower the table.

10 A further object of the invention is to provide a table of the above-mentioned character which is simple and durable in construction, efficient in use and inexpensive to manufacture.

15 Other objects and advantages of the invention will be apparent during the course of the following description.

In the accompanying drawing, forming a part of this specification and in which like numerals 20 are employed to designate like parts throughout the same,

Fig. 1 is a side elevation of the table,

Fig. 2 is a vertical section of one of the swivel joints,

25 Fig. 3 is a top plan view of the table, with a fragment removed,

Fig. 4 is a vertical section of another of the swivel joints, and,

Fig. 5 is a detail view of a modified form of 30 clamp for securing the table to the bed rail.

In the drawing, wherein for the purpose of illustration, I have shown a preferred embodiment of my invention, the numeral 5 denotes a clamping member for securing the table to the tubular side rail 6 of a bed, which consists of a plate 7 having a concaved serrated face 8 held in gripping engagement with the rail by a pair of U-bolts 9 which embrace the rail. The ends of the U-bolts pass through apertures in the plate

40 and have nuts 10 threaded thereon, which adjustably secure the bolts and plate together. An internal screw-threaded collar 11 extends laterally from the outer face of the plate 7 in which is fitted one end of the horizontal pipe extension

45 12. The opposite end of the extension 12 is fitted in the lateral bore 13 of the T-joint 14 which is disposed with the longitudinal bore in a vertical plane. A bearing sleeve 15 is journaled in the longitudinal bore of the joint having a

50 collar 16 surrounding its upper end which rests on the upper end of the joint. A vertical pipe section 17 extends through the sleeve 15 and is adjustably secured therein by the set screw 18 passing through the collar. Thus, it is seen that 55 the pipe section is rotatably supported in the

joint 14, so as to freely turn therein. An elbow joint 19 is attached to the upper end of the pipe section 17, from which extends a second horizontal pipe section 20, connected at its outer end to the T-joint 21. A second vertical pipe section 22 has its lower end 23 enlarged which is journaled in the vertical bore of the joint 21 and a flange 24 is formed integral with the pipe section which rests on the upper end of the joint. A second elbow joint 25 is attached to the upper end of the pipe section 22, from which extends a third horizontal pipe section 26, connected at its outer end to a third T-joint 27. The joint 27 has a bearing sleeve 28 similar to the sleeve 15, journaled in the vertical bore of the joint 27 having a collar 29 at its upper end which rests on the upper end of the joint. A third vertical pipe section 30 passes through the sleeve 28 and is adjustably secured therein by the set screw 31 passing through the collar. The upper end of 20 the vertical pipe 30 is connected to the lateral bore of the T-joint 32, thus disposing the longitudinal bore of the joint on a horizontal plane. A rectangular pipe frame 33 has one end passing through the longitudinal bore of the joint 32 and 25 is firmly supported in a horizontal plane by pins 34 passing through the joint and pipe frame. A flat table top 35 is supported on the frame 33 and is fixedly secured thereto by strap clamps 36.

In Fig. 5, a modified form of clamp is shown 30 for attaching the table to angle iron side members of a bed which consists of a flat plate 37 for engaging the outer side of the angle iron rail 38 and two angle iron plates 39 and 40, the plate 39 being disposed in the angle of the rail 35 and the plate 40 engaging the bottom of the rail. The plates are secured in firm engagement with the rail by bolts 41 passing through the adjoining edges of the plates.

In use, the table is clamped to the side rail 40 of the bed adjacent the head thereof and by reason of the swivel connections between the sections of pipe the table top may be easily swung over the bed into the position desired and when not in use may be swung away from the bed. The 45 first and third sections of vertical pipe may be adjusted vertically to raise or lower the table top as desired.

It is to be understood that the form of my invention herewith shown and described is to be 50 taken as a preferred example of the same and that certain changes in the shape, size and arrangement of the parts may be made without departing from the spirit of the invention or the scope of the subjoined claim.

Having thus described my invention, I claim:—

A bed table comprising a plurality of L-shaped pipe sections pivotally connected together in stepped relation, said sections being capable of individual free swinging movement, a horizontal pipe section having clamping means at one end for attachment to the side rail of a bed, a vertical bearing at the free end of said horizontal pipe section, a bearing sleeve rotatably mounted in said bearing, adapted to receive the vertical member

of the lower L-shaped pipe section, means for adjustably securing the vertical member in said bearing sleeve, a vertical pipe section rotatably mounted in the free end of the horizontal member of the upper L-shaped pipe section, a horizontal pipe frame attached to the upper end of said vertical pipe section, and a table top covering said pipe frame and rigidly attached thereto. 5
